RADIO APPARATUS FOR INTERCOMMUNICATION OR DUPLEX OPERATION

Application filed April 24, 1929, Serial No. 357,635, and in Germany May 5, 1928.

In a radio station intended for duplex operation, the circuits of the receiver and the transmitter are independent of each other. This is necessary since means must be provided so that each of the two apparatus must be capable of being rendered operative, separately and individually, or simultaneously. In the case of a station designed for intercommunication, however, some of the circuits at the transmitter and the receiver are interdependent. For instance, while receiving signals the filament current at the transmitter should be disconnected for the sake of economy. Conversely, while transmitting signals, the filament current of the receiver tubes should be broken. Another point is that, if a common antenna be used, the latter must be connected alternately with the transmitter and the receiver. To accomplish this changeover there is used as a rule what is known as a combination transmitter and receiver switch. This switch may be in practice either an integral constructional part of the transmitter or a separate part. Now, it may happen that a given station is to operate occasionally on the duplex principle and other times on the intercommunication principle. This may be accomplished by providing a separate switch in the receiver by means of which those receiving circuits are closed which would otherwise be interrupted when the sending receiving switch connected with the transmitter is moved into a position permitting independent receiver operation. This switch, provided as indicated above, eliminates or obviates the dependence of the receiver upon the position of the said sending receiving switch and permits duplex operation by the same apparatus which is used for intercommunication.

Whenever it is desired—and this happens quite frequently in practice—that the receiver should be more or less separated from the transmitter when changing from intercommunication operation to duplex operation, the means establishing connection between the said sending-receiving switch and the receiver may be made disengageable preferably by means of plugs adapted to be

inserted in and withdrawn from the corresponding receiver connection sockets.

In this instance, when changing over to duplex operation, it will be necessary to effect two switch motions, i. e., the withdrawal of the plug between sender and receiver, and the closing by the said separate switch of the receiving circuits which are dependent, in intercommunication, upon the position of the sending-receiving switch.

According to the present invention, this circuit change can be accomplished by the aid of a single switch handle manipulation, if arrangements are so made that the act whereby dependence of the receiving circuits upon the sending-receiving switch is caused, is not effected by the agency of a distinct switch to be closed separately, but by that this is effected by the separation of the said connections between said sending-receiving switch and the receiver. In this manner, the change to duplex operation is insured in a wholly automatic manner without the risk of errors, merely by the always necessary physical separation of the receiver by the withdrawal of the plug. Another advantage is that a separate switch to accomplish this operation is unnecessary.

One embodiment of the basic idea of the invention is illustrated by the single figure in the accompanying drawing.

Referring to the drawing,

Of the transmitter T and the receiver R, all circuits not involved in the present invention are omitted. Only the filament circuits of the transmitter and receiver and the plate circuit of the transmitter associated with the sending-receiving switches 4, 5, 6 are illustrated. In intercommunication, the antenna A is used both for sending and receiving, and in duplex traffic the antenna A is only used for sending. Antenna A' is used for receiving in duplex operation.

A number of flexible leads or cords 1, 2, 3 for intercommunication traffic serve to connect the contacts 5, 6 of the sending-receiving switch S, respectively, with the socket contacts 11, 12 and 13 of those circuits of the receiver apparatus which, in intercommunication traffic, must be dependent upon

- the position of this switch S. At the transmitter end, the flexible leads 1, 2, and 3 are connected either permanently or in a disengageable manner with contacts 5, 15 and 16, 5 while at the receiving end they are made disengageable, most preferably by the aid of a suitable plug 7 having three prongs 8, 9, 10, adapted to be inserted in the corresponding contact sockets 11, 12, 13.
- 10 In intercommunication, the sending-receiving switch S for reception is thrown over to the right into a position at which contacts 14, 15, and 16 are closed as indicated by the solid lines, whereby antenna A is connected by way of switch parts 6 and 16, lead 3, plug contact 10, and contact socket 13 with the antenna circuit of the receiver which may include, as shown, the antenna load coil 17, coupler coil 18 and ground G. By 15 the same operation the filament circuit of the receiver tube R₁ is closed by way of socket 12, plug 9, lead 2, contact 15, switch part 5, lead 1, plug 8, socket 11, and battery 19 to 12. The filament circuit which includes 20 battery 20, of the transmitter tube T₁ is broken.
- 25

In this arrangement the receiver R is operative since the filament circuit is energized and signals received on the antenna A are 30 impressed therefrom the inductance 18 to the input circuit inductance I, connected between the input electrodes of the tube R₁, and repeated in tube R₁ to appear in the output circuit connected, as shown, between the 35 anode and cathode of R₁.

When throwing the sending-receiving switch S to the left for transmitting into a position at which contacts 21, 22 and 23 are closed as indicated by the dotted line, the 40 antenna A is inserted in the transmitter antenna circuit through the antenna load coil 24, coupler coil 25, and ground G, while the filament circuit of the transmitter is closed by switch part 4 and the receiver filament 45 circuit is interrupted by switch 5.

In this position of the switch S the receiver is inoperative since the filament circuit is interrupted. The transmitter is operative since the filament circuit of the tube 50 therein is closed. The signal generated or repeated in tube T₁ appears in the anode circuit thereof and is impressed therefrom by inductance IT to the inductance 25 in the antenna circuit.

55 Now, in order that the change to duplexing may be accomplished, according to this invention, only by the removal of the plug connection 7, instead of by switches separately to be actuated, two normally closed contact springs 26 and 27 are provided in the receiving circuits in question. Contact 26 is in the filament circuit. Contact 27 is in the circuit of antenna A'. When plug device 7 is introduced, the contacts 26 and 27 are 60 pressed away by suitable means, as, for exam-

ple, by the aid of lugs 30 secured at the ends of the plugs 8 and 10 as indicated by the blackened portions made from insulating material, from the coating contacts 11 and 12, while they will allow of the automatic closure of these contacts when withdrawing the connector 7. In this manner, duplexing is made feasible automatically by the mere removal of the connector plug 7. Of course, when the plug 7 is removed the receiver R is 75 isolated from the transmitter T. The receiver filament circuit and antenna circuit are closed by the contacts 26 and 27 automatically so that signals may be received. The filament circuit and the antenna circuit 80 of the transmitter are closed by the switch S. The apparatus may be used for intercommunication.

The arrangement as hereinbefore disclosed is suited especially for transportable radio 85 equipments of the kind used, e. g., for military purposes.

Having now fully disclosed my invention and its mode of operation, I claim:

1. In radio apparatus for duplex operation the combination of radio receiving apparatus including a thermionic tube having a cathode normally in circuit with a heating source, and an aerial system normally closed, a radio transmitter including a thermionic 95 tube and an aerial system, and means for adapting said apparatus for intercommunication including a plug connection terminating in contacts in the radio transmitter circuits at the one end and being adapted to 100 be plugged into the radio receiver at the other end, said plug including means operative when plugged in to the receiver to interrupt the receiver antenna circuit and to complete the heating circuit of the thermionic tube in said receiver. 105

2. In combination a radio receiver having an antenna circuit including a biased switch normally closed and a thermionic tube having a heating circuit normally closed through 110 a second biased switch, a radio transmitter including an aerial circuit and a filament heating circuit, a plurality of contacts in said transmitter circuits adapted to be permanently connected to leads which terminate 115 in a plug connection adapted to be inserted in corresponding sockets in said receiver and means on said plug connection for opening the normally closed switch in said receiver aerial circuit on insertion of said plug in 120 the receiving socket.

3. In radio apparatus to be used for duplex operation the combination of a receiver including an aerial circuit normally closed through a spring biased contact, a radio 125 transmitter including a thermionic oscillation repeater and an aerial circuit, and means for adapting said apparatus to intercommunication including a manually operated switch in said transmitter adapted in one po- 130

sition to render said oscillation repeater operative and to connect said transmitter aerial system, and in another position to render said oscillation repeater inoperative and to
5 disconnect said transmitter aerial system, and means for connecting the transmitter aerial to said radio receiver when the manually operated switch is in the last position including a plug connector normally connected to contacts associated with said switch at one end and adapted to be plugged in to sockets in
10 said receiver circuits at the other end.

4. Apparatus as claimed in claim 3 in which said plug includes means for disconnecting said receiver aerial when said plug
15 is inserted in the sockets in said receiver.
